*Primary Examiner—M. H. Tung***[57] CLAIM**

The ornamental design for an angled hand support for a computer mouse, as shown and described.

DESCRIPTION

FIG. 1 is a top, left, front perspective view of an angled hand support for a computer mouse showing my new design on a reduced scale;

FIG. 2 is a left side elevational view thereof, the right side elevational view is a mirror image;

FIG. 3 is a rear elevational view thereof;

FIG. 4 is a front elevational view thereof;

FIG. 5 is a top plan view thereof; and,

FIG. 6 is a bottom plan view thereof, on an enlarged scale.
